UNITED STATES PATENT OFFICE.

ANDREW COCHRAN, OF PHILADELPHIA, PENNSYLVANIA, ASSIGNOR TO JOHN KEUSTER AND WALTER S. GRAHAM, BOTH OF SAME PLACE.

DESIGN FOR A CARPET.

SPECIFICATION forming part of Design No. 14,424, dated November 20, 1883.

Application filed October 4, 1883. Term of patent 3½ years.

To all whom it may concern:

Be it known that I, ANDREW COCHRAN, a citizen of the United States, and a resident of Philadelphia, Pennsylvania, have invented a new and Improved Design for a Carpet-Pattern, of which the following is a specification.

My design is fully shown in the accompanying photographic illustration.

The design comprises the central L-shaped figure, *a*, the surrounding foliated ornamentation, and the bunch of leaves *b*. The ornamentation around the central figure comprises the flowers *d*, leaves *f*, and buds *g*, and the groundwork of the design is ornamented with squares composed of dots. It should be understood that the partial bunches of leaves

shown in the four corners of the design join each other in the complete pattern, so as to form a full bunch of leaves.

I claim—

The design for a carpet-pattern, comprising the central figure, surrounding foliated ornamentation, and leaf-bunches, as shown and described.

In testimony whereof I have signed my name to this specification in the presence of two subscribing witnesses.

ANDREW COCHRAN.
